UNITED STATES PATENT OFFICE.

HAROLD BATCHELOR, OF JERSEY CITY, NEW JERSEY, ASSIGNOR TO ALBERT J. STERLING, OF NEW YORK, N. Y.

METHOD OF AND MEANS FOR EFFECTING CLOSURES.

Application filed September 16, 1924. Serial No. 737,973.

To all whom it may concern:

Be it known that I, HAROLD BATCHELOR, a citizen of the United States of America, residing at Jersey City, in the county of Hudson and State of New Jersey, have invented certain new and useful Improvements in Methods of and Means for Effecting Closures, of which the following is a full, clear, and exact description.

This invention relates to closures for containers, and has particular reference to improvements in means for and methods of effecting the closure of containers for liquids or other contents where an air tight seal is essential.

One object of the invention is to provide an improved way of effecting an air tight seal of containers of the type having a neck or some other portion of the exterior formed with projections or interrupted threads engaged by co-operating portions on the closure cap. Owing to variations in manufacture, trouble has heretofore been experienced in getting uniform and satisfactory seals with closures of the type mentioned, as, so far as known to the applicant, no prior construction has provided a way by which the closure can be satisfactorily adjusted or the seal perfected in spite of such variations. Where the contents of the containers are in liquid form this has necessitated tests and inspection after sealing, and the rejection of all containers where the seal proves imperfect or leaky. Where the contents are not liquid, or are only semi-liquid, but must be protected from the air, a satisfactory test and inspection is very difficult, and for such contents the use of some form of closure other than the cap closure type above mentioned is necessary, such as for example,—a soldered-on top for a firmly inserted cork. This invention provides a convenient and inexpensive way of sealing such contents by a closure cap and at the same time effecting and insuring an air-tight seal regardless of even very considerable irregularities and variations in the co-operating portions of the containers and the closures.

Most of the cap closures of the kind above mentioned employ a cork or a composition insert to form the seal between the closure cap and the mouth of the container. It frequently happens that while the seal will pass first inspection after standing in

storage, the insert will shrink or become affected in such a way that the seal will become imperfect. This usually means recapping; even if the defect is discovered in time to prevent the loss of the contents of the container. If such containers are sealed in accordance with the present invention, the closures may be conveniently tightened periodically, or whenever such tightening appears advisable.

Another object of the invention is to provide an indicator or detector which will show whether the container has been opened. This is so constructed that it affords a protection against unauthorized removal or substitution of the contents of the container.

The invention has other and incidental objects which will be clearly apparent from the following description in connection with the illustrative drawings accompanying and forming a part of this specification:

In said drawings:

Figs. 1, 2 and 3 are respectively top, bottom, and side views of a preferred form of the cap closure.

Fig. 4 is a top view of a container constructed to co-operate with the closure cap shown in Figs. 1, 2 and 3.

Figs. 5 and 6 are respectively a top and a side view of a modified form of the closure cap.

Fig. 7 is a side view of another modification.

Fig. 8 is a top view of a container having a modified form of projection to be engaged by closure caps such as shown in Figs. 5, 6, and 7.

Fig. 9 is a side view of a container such as is shown in Fig. 4.

Fig. 10 is a side view of a container with a closure cap such as shown in Figs. 1, 2, and 3 in sealing position, and also shows one way in which the thief-proof device may co-operate with the container.

Fig. 11 is a side view of the container shown in Fig. 8, with a closure cap such as shown in Figs. 5 and 6, in sealing position.

Stated in general terms, the invention employs a closure cap comprising a band or skirt provided with lugs which may be engaged with corresponding lugs or projections on the neck or some other exterior portion of the container. This engagement may be of such a nature as to form a fairly

satisfactory seal of the container; but to insure and perfect the seal the material of the skirt may be operated upon after the engagement is made so that in effect the skirt is shortened, or rather the distance between the lugs carried by the skirt and the top of the cap is shortened, thereby drawing the inner top of the cap or the sealing insert therein into close engagement with the top of the container. This shortening or bending of the material of the skirt may be different at different points on the periphery of the skirt, thereby adjusting and fitting the cap so as to conform with and compensate for irregularities either at the mouth of the container or in the cap and insert.

The container may have a neck such as shown at 20, Figs. 4, 9 and 10, provided with lugs or projections 21, to be engaged by internally extending lugs 22, Figs. 2, 3, 6 and 7, of a closure cap. The lugs 21 may have their lower walls inclined or otherwise formed, as shown at 23, to serve as cams. The closure cap is first placed over the mouth of the container in such a way that the lugs 22 pass between the projections 21 on the container, and the cap is then rotated until one of the lugs 22 strikes a stop, such as shown at 24. This rotation of the cap will cause the inclined surfaces 23 to pull the cap down so as to bring the cork or other insert 25 in the cap into engagement with the mouth of the container, but this engagement may not be uniform. As so far described, the closure cap and its co-operation with the container is substantially the same as with numerous constructions in the prior art.

The form of improved closure cap shown in Figs. 3, 7 and 10 has a peripheral bead 27, which projects far enough for the top and bottom walls thereof to be engaged by a pair of pliers or other suitable tool for closing up the bead by forcing the top and bottom walls of the bead one toward the other. The lugs 22 on the closure cap co-operating with the projections 21 on the container will cause this closing up of the bead to draw the closure cap into firmer engagement with the mouth of the container. The operation of closing up the bead to shorten the distance between the lugs 22 on the cap and the top 29 of the cap may be performed all at one operation by a suitably constructed tool; but it is preferable to operate upon a portion only of the bead at a time, thereby making it possible to vary the compression of the different portions of the bead, and in that way make it possible to accommodate the seal to irregularities and variations in the conformation of the container mouth or irregularities in insert 25.

The bead 27 is preferably slotted at various points to make the operation of closing

the bead easier to perform, and also to give a certain amount of resilience to the cap. This resiliency will assist in maintaining the closure by co-operation of the lugs 22 with the projections 21, as each portion of the bead between the slots therein has substantially the function of a spring tending to draw or hold the top in firm contact with the mouth of the container and if it is necessary for the bead to be closed up at any of such positions to correct irregularities such closing will insure or increase the spring effect at that point. The material of which the cap is made is preferably one which while having a certain amount of resilience will take a permanent set when it has been operated upon by bending and forming tools. It will be seen that the slots in the bead, divide the bead into a peripherally extending series of beads each substantially independent of the other.

After the closure cap is in sealing position, a tongue 32 will be in close juxtaposition to a shoulder or projection on the neck of the container. This shoulder or projection may be of any suitable shape or location or may be an extension of one of the projections 21, or may be one of the walls of the stop 24. The tongue 32 is connected to the body of the closure cap by a fragile portion of the material, and is preferably distinctively colored so that its presence or absence may be readily detected. This tongue, after the container is sealed, is pushed inward so that it will be in engagement with the stop 24, or corresponding projection on the container, the engagement being such that a removal of the closure cap will cause the tongue 32 to be broken off. The connection between the tongue 32 and the rest of the cap is preferably so fragile so that after the tongue has once been bent into effective position, an attempt to move it to ineffective position will be sufficient to fracture the connection between it and the cap even though at the time no attempt is made to remove the cap.

In Figs. 8 and 11 there is illustrated a container which instead of the projections 21 has a continuous rib 35, the upper surface of which may be formed to act as a cam. The closure cap shown in Figs. 1, 2 and 3 may be used with slight modifications on containers provided with continuous rib 35. The cap would then simply be forced down to carry its lugs past rib 35, when the lugs will snap into engaging position under the rib and thereby hold the closure cap in sealing position.

One modification of the cap when it is intended to use it with the continuous rib 35 is shown in Fig. 7, in which it will be seen that some of the slots in the bead 27 are continued down to the bottom of the skirt, thereby giving more resilient construction.

and permitting the skirt to expand as the lugs 22 pass over the rib 35. Use of the modification shown in Fig. 7 with the continuous rib 35 will, of course, involve a corresponding modification of the lug or projection with which the thief-proof device 32 is engaged after sealing is effected. This modification may also be used with a container having the cam lugs or projections 23 (Fig. 9) so that rotation of this modified form of cap with the lugs 22 thereof in engagement with the cams 23 will draw the closure into firm engagement with the mouth of the container. When so used the separate sections of the skirt formed by extending the slots to the lower edge of the skirt, will permit the resilient bow or head 27 in each section to act to a certain extent independently of the bead in other sections in adjusting the closure and holding it in sealing contact with the mouth of the container.

The form of closure cap shown in Figs. 5, 6, and 11 is a suitable one for use where the material forming the cap is resilient enough to maintain the seal and at the same time is capable of taking a permanent set. Instead of the form of skirt shown in Figs. 3 and 7, the skirt is shortened and is provided with extensions 36, the lower ends of which are formed to provide the lugs 22 for engaging the container and which are bent at an intermediate point, as shown at 38, to form a bead or bow which may be engaged by suitable tools to compress the bead or increase the bow and thereby shorten the distance between the lugs 22 and the top of the cap. This will cause the insert 25 in the closure cap to be adjusted and drawn into firm engagement with the mouth of the container, even though the co-operation of the lugs 22 with the corresponding projection or projections on the container before the crimping operation does not satisfactorily produce that result.

While the foregoing illustrates a means and method for fulfilling satisfactorily the objects primarily stated, it is not the desire to be limited to the embodiments shown and described, as other embodiments and modifications may be satisfactorily employed, all coming within the scope of the claims which follow.

What is claimed is:—

1. The combination with a container having the exterior around its mouth provided with projections the lower walls of which are formed as cams and at least one of which is provided with a vertical wall serving as a stop, of a closure cap provided with lugs for engagement with the cam portions of said projections, whereby rotation of the cap until arrested by the stop will cause the inner top of the cap to be drawn into engagement with the mouth of the container, and a bent portion between each lug and the

top of the cap which may be further bent after the rotation of the cap has been arrested by the stop to draw the closure into closer engagement with the mouth of the container.

2. The combination with a closure cap comprising a skirt formed with a peripherally extending series of out turned beads projecting far enough to permit engagement of the walls of the beads by suitable means for further closing up the beads and having internally extending projections below said beads, and a container having its exterior formed to co-operate with said projections to hold the closure in sealing position on the mouth of the container.

3. The method of sealing containers of the type in which projections extending inward from the closure cap co-operate with corresponding outwardly projecting portions on the neck of the container, which consists in engaging the two sets of projections to seat the cap in sealing position on the container and then bending portions of the metal above the projections to draw the closure into firmer engagement with the mouth of the container.

4. The method of sealing containers of the type in which projections extending inward from the closure cap co-operate with corresponding outwardly projecting portions on the neck of the container, which consists in engaging the two sets of projections to hold the cap in sealing position on the container and then variably bending different portions of the metal above the projections to adjust and draw the closure into uniform sealing engagement with the mouth of the container.

5. The method of sealing a container of the kind which has external projections about its mouth by means of a closure cap comprising a skirt provided with lugs, which consists in placing the cap in sealing position over the container mouth, then engaging the lugs on the skirt with the projections on the container to hold the cap in sealing position and then bending the material of the skirt between said lugs and the top of the skirt to shorten said skirt.

6. The method of sealing a container of the kind which has one or more external projections about its mouth by means of a closure cap comprising a skirt carrying internally extending lugs, which consists in placing the cap over the mouth of the container and engaging the lugs with the projections on the container to hold the cap in position and then bending the material of the skirt between said lugs and the top of the skirt to shorten said skirt.

7. The combination with a container having the exterior around its mouth provided with projections, the lower walls of which are formed as cams and at least one of which

is provided with a vertical wall serving as a stop, of a closure cap provided with lugs for engagement with the cam portions of said projections, whereby rotation of the cap until arrested by the stop will cause the inner top of the cap to be drawn toward the mouth of the container, and a distinctively colored tongue adapted to be engaged behind the stop after the closure is sealed and so connected with the cap that the connection will be broken as an incident to removal of the closure cap.

8. The combination with a container having projections on the outer wall of its mouth, of a closure cap comprising a skirt provided with internally extending lugs engageable under said projections and an out turned bead between said lugs and the top of the skirt and projecting far enough to permit engagement of the top and bottom walls of the bead by tools for forcing the walls of the bead one toward the other to shorten the distance between the lugs on the cap and the top of the cap, and a tongue adapted to be engaged with one of the projections of the container after the container

has been sealed and having a fragile connection with the cap.

9. A closure cap comprising a skirt which is composed of material having resilient properties and provided with inwardly extending lugs for engaging projections on a container, said skirt being bowed and slotted at a plurality of points around its periphery to provide resiliently yielding portions above the lugs on the skirt.

10. A closure cap comprising a skirt made of a material having resilient qualities and provided at its bottom with inwardly extending lugs, said skirt having an annular bead slotted at a plurality of points to form resiliently yielding sections, and a container provided around its mouth with projections having their lower faces formed as cams, said cams acting through the aforesaid resilient sections to draw the top of the closure into engagement with the mouth of the container when the closure is rotated with its projections in engagement with the cams.

In testimony whereof I hereto affix my signature.

HAROLD BATCHELOR.
